UNITED STATES PATENT OFFICE.

FRANCIS FORD, OF BROMPTONVILLE, QUEBEC, CANADA.

FELT GUIDE FOR PULP AND PAPER MACHINES AND THE LIKE.

1,414,940.

Specification of Letters Patent. Patented May 2, 1922.

Application filed March 8, 1920. Serial No. 364,051.

To all whom it may concern:

Be it known that I, FRANCIS FORD, a subject of the King of Great Britain, and resident of the town of Bromptonville, in the 5 Province of Quebec and Dominion of Canada, have invented certain new and useful Improvements in Felt Guides for Pulp and Paper Machines and the like, of which the following is a full, clear, and exact description.

This invention relates to improvements in guiding means for elements of belt form and particularly for the felts of pulp or paper machines.

15 The object of the invention is to provide means for automatically guiding a felt or other element of belt form, whereby it will be returned to proper position on the rolls over which it runs in the event of any tendency to run off the ends of such rolls.

20 A further object is to provide guiding means which are simple, inexpensive, durable and efficient and which may be relied upon to operate satisfactorily with a minimum of attention and with practically no operating expense.

25 The device briefly described comprises a suction box in contact with the running element and a suction line connected to said box and including a water column, at the bottom of which is a reciprocatable member, the position of which is controlled by fluctuations in the effective weight of the column due to fluctuations of pressure in the suction line.

30 This reciprocatable member is arranged to regulate the angular relation between the running element and a supporting roll, whereby the running element may be caused to creep edgewise upon the roll to correct 35 any edgewise displacement.

In the drawings which illustrate the invention;—

Fig. 1 is a side elevation of the device partly in section.

40 Fig. 2 is a plan view thereof.

Referring more particularly to the drawings, 11 designates the various rolls of a machine such as a pulp or paper machine, over which travels a moving element 12 of 45 belt form such as a felt. At any suitable point, an idle roll 13 is provided in sufficient contact with the element 12 to be revolved thereby. One end of this roll is journalled

50 in a bearing 14 pivotally mounted in a preferably rigid bracket or frame member 15, whereby the roll may be oscillated in the plane of movement of that part of the element with which the roll contacts. The opposite end of the roll is journalled in a bearing 16 carried by an arm 17 pivotally supported from a preferably rigid bracket or frame part 18, in such a manner that the free end of the arm may swing and move the roll in a plane substantially parallel with the plane of movement of that part of the element with which the roll engages. The arm 17 has connected thereto a second arm 19, the two arms constituting in the form illustrated a bell crank lever, one extremity of which carries the roll 13. The free extremity of the arm 19, that is to say, the remaining end of the bell crank lever, is connected by a link 20 with a block 21 adjustably mounted on a rod 22, one end of which is guided in any suitable support such as the member 18. The opposite end of this rod 22 is connected to a flexible diaphragm 23 of leather or other suitable material forming the top and closure member of a vessel 24. The interior of this vessel 24 is 55 substantially at the level of and in communication with the bottom of a flask or standpipe 25 which is closed at its upper end. A suction box 26 is provided at any suitable point in communication with the element 12 and is provided with a short air inlet slot 27 disposed to be normally partly covered by the element 12. A suction pipe 28 leads from the bottom of the suction box to the top of the flask 25. A second suction pipe 29 leads from the top of the flask 25 to any suitable vacuum producing apparatus. This pipe may be provided if desired with a valve 30 for severing communication between the suction apparatus and the flask. 60

65 The slot of the suction box is normally practically covered by the element 12 as previously stated and the roll 13 normally extends exactly at right angles to the direction of movement of the element. The vessel 24 and the flask 25 are preferably filled with water to approximately the level shown. The uncovered portion of the slot 27 admits air of a predetermined extent less than the capacity of the vacuum apparatus, so that 70 there is normally a partial vacuum in the 75 flask 25. The flask 25 is provided with a 80 valve 31 for admitting air to the flask 25. The flask 25 is provided with a valve 32 for admitting air to the flask 25. The flask 25 is provided with a valve 33 for admitting air to the flask 25. The flask 25 is provided with a valve 34 for admitting air to the flask 25. The flask 25 is provided with a valve 35 for admitting air to the flask 25. The flask 25 is provided with a valve 36 for admitting air to the flask 25. The flask 25 is provided with a valve 37 for admitting air to the flask 25. The flask 25 is provided with a valve 38 for admitting air to the flask 25. The flask 25 is provided with a valve 39 for admitting air to the flask 25. The flask 25 is provided with a valve 40 for admitting air to the flask 25. The flask 25 is provided with a valve 41 for admitting air to the flask 25. The flask 25 is provided with a valve 42 for admitting air to the flask 25. The flask 25 is provided with a valve 43 for admitting air to the flask 25. The flask 25 is provided with a valve 44 for admitting air to the flask 25. The flask 25 is provided with a valve 45 for admitting air to the flask 25. The flask 25 is provided with a valve 46 for admitting air to the flask 25. The flask 25 is provided with a valve 47 for admitting air to the flask 25. The flask 25 is provided with a valve 48 for admitting air to the flask 25. The flask 25 is provided with a valve 49 for admitting air to the flask 25. The flask 25 is provided with a valve 50 for admitting air to the flask 25. The flask 25 is provided with a valve 51 for admitting air to the flask 25. The flask 25 is provided with a valve 52 for admitting air to the flask 25. The flask 25 is provided with a valve 53 for admitting air to the flask 25. The flask 25 is provided with a valve 54 for admitting air to the flask 25. The flask 25 is provided with a valve 55 for admitting air to the flask 25. The flask 25 is provided with a valve 56 for admitting air to the flask 25. The flask 25 is provided with a valve 57 for admitting air to the flask 25. The flask 25 is provided with a valve 58 for admitting air to the flask 25. The flask 25 is provided with a valve 59 for admitting air to the flask 25. The flask 25 is provided with a valve 60 for admitting air to the flask 25. The flask 25 is provided with a valve 61 for admitting air to the flask 25. The flask 25 is provided with a valve 62 for admitting air to the flask 25. The flask 25 is provided with a valve 63 for admitting air to the flask 25. The flask 25 is provided with a valve 64 for admitting air to the flask 25. The flask 25 is provided with a valve 65 for admitting air to the flask 25. The flask 25 is provided with a valve 66 for admitting air to the flask 25. The flask 25 is provided with a valve 67 for admitting air to the flask 25. The flask 25 is provided with a valve 68 for admitting air to the flask 25. The flask 25 is provided with a valve 69 for admitting air to the flask 25. The flask 25 is provided with a valve 70 for admitting air to the flask 25. The flask 25 is provided with a valve 71 for admitting air to the flask 25. The flask 25 is provided with a valve 72 for admitting air to the flask 25. The flask 25 is provided with a valve 73 for admitting air to the flask 25. The flask 25 is provided with a valve 74 for admitting air to the flask 25. The flask 25 is provided with a valve 75 for admitting air to the flask 25. The flask 25 is provided with a valve 76 for admitting air to the flask 25. The flask 25 is provided with a valve 77 for admitting air to the flask 25. The flask 25 is provided with a valve 78 for admitting air to the flask 25. The flask 25 is provided with a valve 79 for admitting air to the flask 25. The flask 25 is provided with a valve 80 for admitting air to the flask 25. The flask 25 is provided with a valve 81 for admitting air to the flask 25. The flask 25 is provided with a valve 82 for admitting air to the flask 25. The flask 25 is provided with a valve 83 for admitting air to the flask 25. The flask 25 is provided with a valve 84 for admitting air to the flask 25. The flask 25 is provided with a valve 85 for admitting air to the flask 25. The flask 25 is provided with a valve 86 for admitting air to the flask 25. The flask 25 is provided with a valve 87 for admitting air to the flask 25. The flask 25 is provided with a valve 88 for admitting air to the flask 25. The flask 25 is provided with a valve 89 for admitting air to the flask 25. The flask 25 is provided with a valve 90 for admitting air to the flask 25. The flask 25 is provided with a valve 91 for admitting air to the flask 25. The flask 25 is provided with a valve 92 for admitting air to the flask 25. The flask 25 is provided with a valve 93 for admitting air to the flask 25. The flask 25 is provided with a valve 94 for admitting air to the flask 25. The flask 25 is provided with a valve 95 for admitting air to the flask 25. The flask 25 is provided with a valve 96 for admitting air to the flask 25. The flask 25 is provided with a valve 97 for admitting air to the flask 25. The flask 25 is provided with a valve 98 for admitting air to the flask 25. The flask 25 is provided with a valve 99 for admitting air to the flask 25. The flask 25 is provided with a valve 100 for admitting air to the flask 25. The flask 25 is provided with a valve 101 for admitting air to the flask 25. The flask 25 is provided with a valve 102 for admitting air to the flask 25. The flask 25 is provided with a valve 103 for admitting air to the flask 25. The flask 25 is provided with a valve 104 for admitting air to the flask 25. The flask 25 is provided with a valve 105 for admitting air to the flask 25.

flask above the water column, with the result that air pressure on the diaphragm 23 supports part of the weight of the column of water. If the element 12 should creep 5 laterally on its supporting rolls 11, it will either decrease or increase the amount of slot 27 uncovered and will thereby vary the amount of vacuum above the water column. If the uncovered portion of the slot is increased, the greater inertia of air reduces 10 the vacuum in the flask 25, so that more than the weight of water column is thrown upon the diaphragm 23 and the diaphragm is thereby bulged upwardly and shifts the rod 15 22. The rod movement is communicated through the link 20 and arm 19 to the arm 17, so that the roll is swung out of its exact transverse relation with the element 12. It is well known that a belt tends always to 20 travel at right angles to the axis of a supporting roll and that, as a result of this tendency, a belt will creep edgewise on a supporting roll in an endeavor to find a position in which it will travel exactly at right angles 25 to the axis of the roll. As soon as the roll is shifted, the element 12 commences to creep edgewise thereon and is thus returned to its proper relation with the suction slot 27. As the exposed area of the slot 27 gradually 30 decreases, the vacuum effective above the water column increases, so that air pressure on the diaphragm 23 causes a gradual movement of the same to restore the parts to their original positions. In this way, the 35 correcting influence is proportional to the amount of lateral displacement of the element 12, so that there is no tendency for the correction to be exaggerated and produce a second displacement opposite to the 40 first. If the lateral displacement of the element 12 should produce a reduction of the exposed portion of the slot 27, the inrush of air will obviously be decreased and the vacuum above the water column increased, 45 with the result that air pressure on the diaphragm 23 will depress the same and produce an angular displacement of the roll 13 opposite to that previously described.

From the foregoing description, it will 50 be readily seen that the device is extremely simple, durable and inexpensive in its construction and includes no parts liable to get out of order. The form illustrated is designed with special reference to pulp and 55 paper machines where constant pressure suction apparatus is already installed. The amount of air flowing through the device is at no time very great, so that no increase of power is required to produce the desired 60 vacuum. When the device is installed on a pulp or other wet machine, the device will automatically keep itself supplied with water which will be drawn from the element 12 through the covered portion of the slot 27 65 into the flask 25. Any excess of water will

flow away through the suction pipe 29 and may be discharged through the vacuum apparatus or through a suitable trap. When the device is in use on a dry machine, the water lost by evaporation should be replaced 70 from time to time to ensure an effective height of water column.

While the parts of the device have been shown in a certain specific relation, it will be understood that this relation may be altered as desired without departing from the spirit of the invention. Obviously, the diaphragm is merely the equivalent of a piston and may be replaced by a piston of sufficient area without altering in any way 75 the principle or operation of the device. The use of the diaphragm is, however, preferred as it has the more simple and less expensive construction and also eliminates friction and leakage losses. It will also be understood 80 that the invention will function quite as well if the pressures maintained over the water column are super-atmospheric instead of sub-atmospheric.

Having thus described my invention, what 90 I claim is:—

1. In a device of the class described, a guide roll adapted to engage an element to be regulated, adjustable supporting mechanism for said roll including a reciprocating member, a water column arranged to reciprocate said member, and means for varying air pressure above said column including a conduit having an opening to the atmosphere located to be normally partly covered by an element to be regulated.

2. A felt strip mounted on rolls, an adjusting roll for maintaining said strip on said rolls, a hydraulic machine having a standing water column operatively connected to said adjusting roll and a vacuum member in operative engagement with said fluid pressure member and regulated by the felt strip in passage thereon.

3. A felt strip mounted on rolls, an oscillating roll for maintaining said strip on said rolls, a hydraulic machine oscillating said roll and a vacuum box having an opening normally covered by said strip and connected to said strip and controlled thereby for changing the pressure in said hydraulic machine in the displacement of the strip.

4. A felt strip mounted on rolls, an adjusting roll for maintaining said strip on said rolls, a fluid pressure formed of a vessel containing a water column connected with a diaphragm chamber and a vacuum member actuated by said fluid pressure member and regulated by the felt strip in passage thereon.

5. A felt strip mounted on rolls, an adjusting roll for maintaining said strip on said rolls, a fluid pressure formed of an enclosed water column and a diaphragm a lever reciprocated by said diaphragm and a

vacuum member actuating said fluid pressure member and regulated by the felt.

6. A felt strip mounted on rolls, an adjusting roll for maintaining said strip on

5 said rolls, a fluid pressure, a post and levers operative by said diaphragm and operatively connected to said adjusting roll, a lever re-

ciprocated by said diaphragm and a vacuum member actuating said fluid pressure member and regulated by the felt strip in passage thereon. 10

In witness whereof, I have hereunto set my hand.

FRANCIS FORD.
